METHOD OF SEWING HAT-LEATHERS INTO HAT-BODIES.

1,139,662.

Specification of Letters Patent. Patented May 18, 1915.

Application filed May 3, 1913. Serial No. 765,237.

To all whom it may concern:

Be it known that I, WELCOME P. GAMMONS, Jr., citizen of the United States, residing at New York, in the county of New York and State of New York, have invented 5 certain new and useful Improvements in Methods of Sewing Hat-Leathers into Hat-Bodies; and I do hereby declare the following to be a full, clear, and exact description 10 of the invention, such as will enable others skilled in the art to which it appertains to make and use the same, reference being had to the accompanying drawing, and to figures of reference marked thereon, 15 which form a part of this specification.

This invention relates to an improved method for sewing hat leathers into hats by means of which the appearance of the hat is enhanced by reason of the hat leather showing 20 no burs or light spots at the perforations where the stitching is done, as the method causes the burs of the leather to project at the stitch openings on the side toward the hat body.

The improved method of sewing the hat provides an improved form of hat, the sewing operation consisting of two distinct steps, first puncturing the leather when it is 25 in position in the hat, the puncturing taking place toward the body, whereby a resistance, even if it is slightly yielding, is formed for the puncturing operation, the bur being formed on the hat leather toward the hat by reason of the puncturing tool entering 30 the leather on the side farthest from the hat. Second, stitching first through the hat and then through the hat leather, the stitch through the hat leather going through the 35 perforation previously made by the puncturing tool.

The method of carrying out the invention is illustrated in the accompanying drawing, in which—

Figure 1 is a section showing a hat leather 45 and enough of a hat body to illustrate the relation of the parts, this view showing the leather before it is punctured. Fig. 2 shows the parts in similar relation as in Fig. 1, but with the hat leather and part of the hat body 50 punctured and the needle advanced to show the stitch. Fig. 3 is a similar view after the stitch is made, and Fig. 4 is the stitched hat

removed from the sewing mechanism and in its normal position.

In this invention I have not illustrated 55 nor will I describe the particular mechanism to bring about the operations incidental to the construction of the hat, and the method of sewing hat leather in the body, since different forms of apparatus and sewing machines can be used for this purpose, but as types illustrating the general machine in use, I will refer to my Patent No. 999,024, issued July 25, 1911, and the structure illustrated in United States Letters Patent No. 65 1,063,253, issued June 3, 1913.

In carrying out my invention I provide a hat of the usual type, either a soft hat or a stiff hat, or the device is used as applied to a soft hat which is usually inverted when placed in the usual type of sewing machine for hats, and I illustrate the hat in its inverted position, illustrating part of the crown 10 and the brim 11, these being folded over on the edge of a suitable feeding wheel 75 12, the feeding wheel being used to advance the hat by a step-by-step movement to bring the successive portions of the hat in line with the puncturing and stitching means. I hold, by a suitable mechanism, the hat 80 leather 13 so that it is in place in the hat body.

The first operation consists in puncturing the hat leather, for which purpose I use an awl 14, or a similar tool which is advanced 85 so as to enter the hat leather from the side opposite the hat body, whereby the hat body forms a somewhat resilient backing for the puncturing operation and also provides enough "give" to permit the burs 15, which 90 are shown in Fig. 2, to be formed on the side toward the hat body, the puncturing operation entering, usually, a slight distance into the hat body as at 16 in Fig. 2. The hat leathers are usually made with a darkened 95 surface due to the tanning process, and the finish of the leather, the inside of the leather being of a lighter color, and since the leather is thin, if the puncture is made by a sewing implement, as a needle, it pushes the material out away from the hat and it causes, as can be usually seen in the average type of new hat, a series of burs which are apparent to the touch when the finger is run 100

across the edge of the leather and which also is evident to the eye, since the light color of the inside leather is pushed out, and a series of what appears to be small white dots are arranged where the stitches come through the leather. In my improved method this is prevented by reason of the bur being forced toward the hat where it can not be seen nor felt.

10 When the awl 14 retreats, due to the sequence of operation of the sewing machine parts, the needle 17 advances, the needle 17 being threaded as usual and adapted to make a stitch by its co-operation with a suitable looper. The needle 17 is so arranged that it enters the hat body first, that is, it enters from the side opposite the hat leather and at a point in line with the perforation or recess 16 and in line with the perforation 18 that is made in the hat leather by the awl 14. The needle coming through the perforation has a clear passage and does not force the bur 15 outward, and the sewing operation does not disturb this portion of the hat leather. When the needle is withdrawn and the stitch is made, it appears as in Fig. 3, the stitch being illustrated at 19 and folding the end of the hat leather down against the juncture of the brim and the body as 30 at 20.

In Fig. 4 I illustrate a part of the hat body and the leather when the hat is removed from the machine and with the brim assuming its normal position or approximately its normal position, illustrating the burs on the hat leather somewhat embedded in the hat body, leaving a smooth surface on the inner edge of the hat leather.

It will be understood in these drawings 40 that some parts are exaggerated, for instance, the thickness of the thread and the size of the opening through which it comes in the hat leather, these being exaggerated to more clearly define the invention, but in practice the opening through which the thread comes and the thread itself are not so apparent.

After the stitch is taken, a suitable feeding mechanism turns the feeding wheel 12 50 the distance of between one stitch and the next, and the operation of puncturing and sewing is repeated until the hat leather has been secured for its entire length in the in-

side of the crown of the hat. The puncturing of the hat leather can not be done previous to the sewing, because in feeding a hat in a hat sewing machine, if the punctures in the hat leather were made previously, and even if the needle was started off to penetrate each succeeding perforation when it began, it would not register with these equidistant perforations when the smaller radii of the hat were reached, that is, in the front and the rear of the hat the radius is small, and besides, there is a dip or drop to the hat 60 brim which interferes with the feed and which would prevent the needle from stepping into its successive holes, and the result and product would not be acceptable.

Having thus described my invention, what I claims is:—

1. The improved method of securing hat leathers into hat bodies consisting in placing the leather in the hat with the edge of the leather adjacent to the juncture of the crown of the hat with its brim, subjecting the leather to a puncture first through the leather toward the hat, withdrawing the punch, sewing through the body and then through the puncture in the leather when the punch is withdrawn, then advancing the hat and leather for the length of a stitch and then repeating the puncture and sewing operation described.

2. The improved method of securing hat leathers into hat bodies consisting in placing the leather in the hat with the edge of the leather adjacent to the juncture of the crown of the hat with its brim, folding the brim toward the hat, puncturing the leather 90 toward the fold of the hat and partially into the hat body, withdrawing the punch, then sewing through the hat body and then through the perforation in the hat leather when the punch is withdrawn, then advancing the hat and leather for the length of a stitch and then repeating the puncturing and sewing operation described above.

In testimony, that I claim the foregoing, I have hereunto set my hand this 29th day of April, 1913.

WELCOME P. GAMMONS, JR.
